UNITED STATES PATENT OFFICE

FREDERICK RAHM AND ALLEN CLIFTON PILCHER, OF LOUISVILLE, KENTUCKY, AS-
SIGNORS TO PRECISION SYRUP PUMP COMPANY, OF JEFFERSON COUNTY, KEN-
TUCKY

SIRUP PUMP

Application filed September 19, 1929. Serial No. 393,637.

Our invention relates to syrup pumps in which the delivery piston moves a fraction of the plunger's movement by means of which the piston is actuated.

5 An object of the invention is to provide a syrup pump which is simple in construction and easy stroking operation and will permit an adjustment in the piston displacement.

In the appended drawing, Figure 1 is a 10 horizontal section on line 1—1, Figure 2.

Figure 2 is a vertical section on line 2—2, Figure 1, and

15 Figure 3 is a fragmentary elevation of the lazy tong structure as seen on line 3—3, Figure 2.

Referring to the figures, 5 is the cylinder, the bottom 6 of which is provided with a 20 gravitationally operable inlet valve 7. The open top of the cylinder 5 is spanned by a bridge 8 through the center of which the rod 9 of a piston 10 projects. The bridge 8 has a tubular extension 11 to one end thereof extending into the cylinder through the piston. In this tubular extension a seat is formed for 25 an outlet ball valve 12. The tubular extension 11 above the bridge 8 is connected to a delivery tube 13 which enters a nozzle 14 of a jar cover 15. To maintain a rigid connection between the cylinder and the jar cover 30 15, a stay 16 is interposed between the cover and the bridge 8.

The cover 15 has a tubular housing 17 in the central part thereof above and below the cover. The depending portion 18 of said housing is threaded exteriorly to engage a cap 19. A plunger 20 projects through the cap and housing 17 and out through the top of the housing. The plunger 20 at the end projecting above the housing 20 carries a 40 button 21 which has a sleeve 22 adapted to telescope within the housing 17. A spring 23 within the housing on the plunger normally extends the major part of the sleeve 23 out of the housing 17 thereby maintaining the end 24 of the plunger against the cap 19.

Collapsible means such as lazy tongs 25 connects the end 24 of the plunger to a brace 26 extending between the delivery tube 13 and the stay 16. Links 27 connect the piston

rod 9 to the lazy tongs so that the piston travels only a fraction of the distance of the plunger's displacement.

The walls of the cylinder 5 to each side of the bridge 8 are cut away as best shown in 55 Figure 1 to provide an opening 28 at the top of this cylinder below the bridge 8. Thus, normally, the piston is moved out of the cylinder by the spring 23. In consequence, at the beginning of the piston's motion, there 60 is no outflow from the cylinder until the piston 10 enters the cylinder when the liquid enclosed in the cylinder by the piston is forced through the tubular extension 11, valve 12, delivery tube 13 and in and through 65 the nozzle 14.

We claim:

1. In a syrup pump, a cylinder open at the top, an inlet valve in the bottom of cylinder, a bridge above the cylinder and connected thereto, a piston in the cylinder having a rod projecting through the bridge, a tubular extension from the bridge into the cylinder through the piston, an inlet valve in 70 said tubular extension, a cover having a nozzle, a delivery tube from the tubular extension to the nozzle, a stay from the cover to the bridge, a brace connecting the delivery tube to the stay, a housing on the cover, a plunger in the housing, lazy tongs connecting the plunger to the brace, links connecting the piston rod to the lazy tongs above the 75 brace, a spring between the housing and plunger normally moving the end of plunger connected to the tongs toward the housing 80 and a cap adjustable on the housing engaging the said end of plunger.

2. In a syrup pump a cylinder open at the top and having an inlet valve in the bottom thereof, a bridge above the cylinder connected thereto, a piston in the cylinder having a rod projecting through the bridge, a tubular extension from the bridge into the cylinder through the piston, an inlet valve in 90 said tubular extension, a cover having a nozzle, a delivery tube from the tubular extension to the nozzle, a plunger in the cover, collapsible means connecting the plunger to the piston rod, a spring on the plunger for 95 normally moving the piston by the collapsi- 100

ble means out of the cylinder to the bridge and means for adjusting the movement of the plunger by the spring.

3. In a sirup pump, a cylinder having an inlet and an outlet valve, a piston mounted to reciprocate in the cylinder, a plunger, collapsible means connecting the plunger to the cylinder, and means connecting the collapsible means to the piston, for moving the piston in both directions.

4. In a sirup pump, a cylinder having an inlet and an outlet valve, a piston mounted to reciprocate in the cylinder, a spring actuated plunger, lazy tongs having one end thereof connected to the plunger and the other one rendered stationary, and means connecting the piston to the lazy tongs between its ends.

5. In a sirup pump, a cylinder having an inlet and an outlet valve, a piston mounted to reciprocate in the cylinder, a spring actuated plunger, lazy tongs having one end thereof connected to the plunger and the other end made stationary, means connecting the piston to the tongs between the ends thereof, and means for adjusting the plunger's displacement.

6. In a sirup pump, a cylinder having an inlet and an outlet valve, a piston, a spring actuated plunger, lazy tongs connecting the plunger to the cylinder, and means connecting the lazy tongs to the piston, so that the piston will travel only through a fractional distance of the plunger's displacement.

FREDERICK RAHM.
